[57] **ABSTRACT**

A stick horse on which a person rides with a bouncing movement, comprising an elongated rod made of resilient material which the rider straddles and holds so that the rod has one end resting on the ground and the other end inclined upwardly from the ground, a head on the upwardly inclined end of the rod simulating an animal head, and a seat mounted intermediately along the length of the rod on which the rider alternately sits to apply a downward thrust to the rod bending same, and then raises himself slightly from the seat whereupon the rod bends upwardly under elastic stress.

JUMPING STICK HORSE

This invention relates to an improved stick horse such as used by children to simulate a real horse and on which the child rides with bouncing motion.

Stick horses have been used by children in the past in the make-believe sport of simulated horseback riding. The stick horses commonly found in the prior art include a rigid stick which is held in the hands of the rider near one end in an inclined position with the other end resting on the ground. The stick will usually be provided with a head simulating a horse's head, or other animal head and sometimes may even be provided with a seat. The sticks are ridden with a galloping motion by the riders but being rigid they provide no propulsion to the rider.

It is an object of this invention to provide an improved stick horse which provides the rider with propelling motion under the rider's weight.

It is a further object of the invention to provide a riding toy which is made of an elongated resilient rod which springs vertically under the weight of the rider.

With the foregoing objects and features in view and such other objects and features as may become apparent as this specification proceeds, the invention will be understood from the following description taken in conjunction with the accompanying drawing, wherein like characters of reference are used to designate like parts and wherein;

FIGS. 1 through 4 are a series of side elevational views of a rider on the invention showing a sequence of positions of the rider and invention in normal use of the invention;

FIG. 5 is a sectional view of the invention taken on line 5—5 of FIG. 1; and

FIG. 6 is a sectional view similar to FIG. 5 of a modified form of the invention.

Referring now to FIG. 1 of the drawing a rider 10 is shown straddling the invention 11 which comprises an elongated rod 12 having a simulated horse's head 13 mounted on one end 14 of the rod and a seat 15 mounted securely intermediately along the length of the rod. In use the end 16 of the rod opposite the simulated horse's head rests on the ground 17 or other suitable supporting surface such as the floor of a building. The seat 15 has a generally flat surface 19 supported by a depending member 20 on the inclined upper surface of the rod 12 when the stick horse is held in position for use. The seat is preferably adjustably mounted along the length of the elongated rod 12 by means of clamps 18 which encircle the rod and are bolted to the depending seat support member 20. If desired a screw fastener 21 may be extended through one or both of the clamps 18 to fix the clamp at a selected position along the length of the rod 12. However adjustability of the seat with respect to the rod 12 is preferred in order to adjust the seat position for use with riders of varying height.

The invention is particularly characterized by the resilient nature of the rod 12 which is adapted to bend under weight in a vertical plane when held in position for normal use as shown in FIG. 2. The rod 12 may be of circular cross section as seen in FIG. 5 in which case

the rod is universally resilient in any plane containing the rod or the rod 12 may be flat with a rectangular cross section as shown in FIG. 6. Cross sectional configurations and lengthwise shapes for the rod 12 other than those shown in the drawing may be used provided the rod is capable of bending resiliently in a vertical plane when the rod is held in position for normal use by the rider. As shown in FIG. 6 the seat 15 is secured to the rod 12 by means of a headed fastener 22 extending through the rod 12 into the support 20 depending from the seat.

The strength of the spring material selected for the rod 12 will be chosen in accordance with the weight of the rider for whom the stick horse is designed. For example the rod 12 may be made of elastic metal, plastic or other spring material approximately 5 feet long and of approximate 1 1/2 inch diameter. The elastic strength of the rod 12 for children from six to ten will be stronger than for children from three to six years of age because of their difference in weight. Other dimensions of length and cross section can be chosen as will be apparent to those skilled in the art.

The use of the stick horse 11 is best understood by viewing FIGS. 1, 2, 3 and 4 in sequence. The rider on mounting the stick horse stands straddling the horse holding the head 13 upwardly as shown in FIG. 1. The rider then bends his knees and puts weight on the seat 15 causing the rod 12 to bend as shown in FIG. 2. A slight upward and forward movement of the rider upon his legs takes weight off the seat 15 and permits the rod 12 to spring upwardly as shown in FIG. 3 giving the rider an upward and forward thrust. The rider then bends his knees and applies weight to the seat 12 as seen in FIG. 4 causing the rod 12 to bend and preparing it to repeat the cycle. As the rider progresses forwardly with a running or galloping motion in the manner described, the stick horse provides bounce to the ride by means of its resiliency.

What is claimed is:

1. A jumping horse comprising a flexible, elastic, springy resilient rod of a length for one end to rest on the floor behind a child straddling the bar and extend upwardly at an acute angle through the crotch of the child forwardly and upwardly for gripping of the upper forward end portion by the hands of the child, a seat having a generally horizontally extending seat portion mounted on a mid portion of said flexible springy rod at an acute angle to the rod with the seat portion substantially parallel with the floor and behind the child when the child is standing and gripping the forwardly projecting portion of the

2. The invention according to claim 1 in which an animal head is mounted on the flexible, elastic, springy resilient rod forwardly of the portion of the rod gripped by the hands of the child with the animal head in upright position when the seat portion is horizontal.

3. The device set forth in claim 1 together with means for adjustably mounting said seat at selected positions along the length of said rod.

4. The device set forth in claim 1 wherein said rod has a rectangular cross section with the sides of greater dimension extending horizontally.

UNITED STATES PATENT OFFICE
CERTIFICATE OF CORRECTION

Patent No. 3,682,474 Dated August 8, 1972

Inventor(s) James R. Campbell

It is certified that error appears in the above-identified patent and that said Letters Patent are hereby corrected as shown below:

Column 2, line 51, after "the", insert the following:

-- rod while the said one end of the rod engages the floor, said flexible resilient bar having a small vertical dimension relative to the width whereby the bending is limited to flexing in a vertical plane, the rod being sufficiently flexible in a vertical plane while also being sufficiently stiff so the child may bounce on the seat by assuming a sitting position while straddling the bar and gripping the upper forward end and thereby flexing the mid portion of the rod downwardly by his weight and downward momentum by a sufficient amount so the seat springs upwardly by the resilience of the rod moving the child upwardly to an upright position so the operation can be repeated a number of times, producing a pleasant amusement experience. --

Signed and sealed this 24 th day of April 1973.
